UNITED STATES PATENT OFFICE.

THADDEUS V. ELLIOTT, OF BROOKLYN, NEW YORK, ASSIGNOR, BY MESNE ASSIGNMENTS, TO WILLIAM F. MARSH AND CLARENCE McMILLAN, OF NEW YORK, N. Y.

TURBINE.

1,084,200.

Specification of Letters Patent.

Patented Jan. 13, 1914.

Application filed August 4, 1910. Serial No. 575,452.

To all whom it may concern:

Be it known that I, THADDEUS V. ELLIOTT, a citizen of the United States, residing in Brooklyn, in the county of Kings 5 and State of New York, have invented certain new and useful Improvements in Turbines, of which the following is a specification.

The object of this invention is to provide 10 an improved form of rotary fluid pressure motor, that will be simple and cheap in manufacture and highly efficient in its action.

Another object of the invention is to provide 15 an improved form of rotor in which the blades are attached to the ring by being molded therein by casting.

Another object is to provide an improved 20 construction in which the inlet passes axially at one side, and the outlet for the fluid is on the opposite side in an axial direction.

A further object is to provide improved 25 means for securing the jet members in the rotor.

In the accompanying drawing representing 30 embodiments of my invention, Figure 1 is an end elevation of the device applied to a fan. Fig. 2 is a side elevation partly broken away. Fig. 3 is a section through 35 the motor portion of the device taken on the line 3—3 indicated in Fig. 1. Fig. 4 is a section on the line 4—4 indicated in Fig. 3. Fig. 5 is a section on the line 5—5 of Fig. 3. Fig. 6 is a broken section on the line 6—6 indicated in Fig. 4. Fig. 7 is a perspective 40 view of one of the blades and Fig. 8 is a longitudinal section through the same. Fig. 9 is a cross section enlarged of one of the blades.

The device is shown applied to a fan in 45 Figs. 1—3 in which there is a frame member 1 having radial arms 2 on each side that support the shaft member 3. At the center is the motor denoted generally by 4 to the 50 periphery of which the fan blades 10 are secured. But this fan forms no part of the present invention, that relates only to the motor, which can be used to furnish power for any purpose desired. The motor 4 is shown as comprising a stator 5 that is in-

tegral with the shaft 3, and which is enclosed at its middle portion by the rotor 6. The latter practically has two parts comprising members 7 and 8 that are connected at their periphery by a ring member 9 to 55 which are secured the blades 10. The stator 5 is shown as comprising a ring portion 11 having a hollow shaft portion 12 extending from one side that forms an inlet for the fluid, which inlet connects with two radial 60 passages 13 and 14 leading to chambers 15 and 16 at their respective ends. The chamber 15 connects with two jet outlets, shown best in section of Fig. 6. These jets are formed by pipes or nozzles 17 and 18, that 65 are shown as projecting from the opposite side faces of this ring portion 11, making a sharp angle with the plane of rotation and extending in the same circular direction. In the specific construction set forth, just beyond the chamber 15, that has its end walls 19 and 20 inclined, are notches 21 and 22 in the ring member, into which the jet members 17 and 18 extend. These nozzles can be inserted in apertures in these walls 23 70 and 24 if desired, but in the construction shown a plug 25 is passed through the two walls transverse to the faces of the ring, and contains bores through which the jet pipes 17 and 18 extend. This arrangement is for 75 80 convenience of construction. At the other chamber 16 the jet pipes 27 extend from a plug 28 similar to the construction just described.

The rotor 6 is shown as comprising two 85 ring members 7 and 8 each of which are practically identical. The member 7 has a bearing portion 30 engaging the hollow shaft 12 and may be secured in position by a clamp collar 31. This member has its side 90 face arranged opposite one side face of the stator containing the jet pipes, and such face contains a circular channel 32, in which are arranged the blades to receive the fluid jets. In the form shown, the blades 33 95 have their extremities secured in the opposite side walls of the channel. The blades are shown in Figs. 7—9 as somewhat cup-shaped but elongated, having extensions 34 and 35 at their extremities. These exten- 100

sions project into suitable sockets in the side walls of this channel portion, and are preferably secured therein by being cast in the member, the blades or buckets being placed 5 in the mold and the ring member cast thereon. These blades are shown inclined to the jets, as indicated in Fig. 10. This channel 32 in the member 7 of the rotor connects by ports 36 with an inner channel 37 to receive the fluid after leaving the buckets.

The rotor member 6 has its buckets 38 formed and arranged in the same manner to receive the fluid from the jet pipes on that side. This member has a bearing member 39 15 riding on the hollow shaft portion 40 extending from the stator 5. The member 6 has an inner annular channel 41 connected by ports 42 with the channel 38 for receiving the fluid after leaving the bucket. The member 6 also has radial ports 44 connecting the channel 41 with the tubular member 40, providing exit for the fluid from the buckets 20 in this member 6. The fluid from the other rotor member 7, passes through open portions 45 and 46 in the stator member across to the channel portion 41 and finds exit from this portion through the hollow shaft 40. By this means it will be seen that the fluid under pressure for the motor enters through 25 the hollow shaft of the stator, passes to the peripheral chamber in the same, thence through jets against the buckets or blades of the rotor sections, and thence through the rotor and through openings in the stator to 30 the hollow shaft of the stator on the opposite side, where it finds exit.

Having thus described my invention, I claim:

1. In a rotary motor, the combination of 40 a stator comprising a ring member containing therein passages for the fluid, jets on one side face of the stator inclined to the plane of the ring and extending in the same circular direction, a rotor comprising a ring member arranged to rotate with its side face adjacent the side face of the stator containing the jets, the rotor having a circular channel in said side face containing therein buckets arranged to receive the fluid from 45 the jets successively on rotation of the rotor, the rotor having an outlet passage leading from the opposite side of the buckets.

2. In a rotary motor, the combination of 55 a stator comprising a ring member containing therein passages for the fluid, jets on one side face of the stator inclined to the plane of the ring and extending in the same circular direction, a rotor comprising a ring member arranged to rotate with its side face adjacent the side face of the stator containing 60 the jets, the rotor having a circular channel in said side face containing therein buckets arranged to receive the fluid from the jets successively on rotation of the rotor,

the rotor having an outlet passage leading 65 from the opposite side of the buckets, the stator having an axial inlet passage communicating with the outlet jets.

3. In a rotary motor, the combination of 70 a stator comprising a ring member containing therein passages for the fluid, jets on one side face of the stator inclined to the plane of the ring and extending in the same circular direction, a rotor comprising a ring member arranged to rotate with its side face 75 adjacent the side face of the stator containing the jets, the rotor having a circular channel in said side face containing therein buckets arranged to receive the fluid from the jets successively on rotation of the rotor, 80 the rotor having an outlet passage leading from the opposite side of the buckets, the stator having an axial outlet passage communicating with the side passages beyond the buckets.

4. The combination with a stator having 85 an internal passage for the fluid, said stator having a pair of inclined sockets in the opposite side faces beyond the said passage, and having a transverse bore in the walls 90 separating the passage from the said socket portions, said bore having a plug fixedly located therein and a jet pipe on each side passing through the said plug and located in the socket portion.

5. In a rotary motor, a stator comprising 95 a shaft having a ring portion at its middle part, a passage for the fluid at the outer portion of the ring, jet members leading from the passage to the two side faces of the ring portion inclined to the diametral plane of the stator in the same circular direction, the stator having an inlet passage communicating with the said passage in the outer portion by radial passages, the stator also having lateral passages from one side to the other at an intermediate portion, a rotor comprising a circular member rotating on the shaft of the stator on each side of the stator and inclosing the same, the rotor having a circular series of blades on each side adjacent the said two side faces containing the jets, the blades being in position to receive the fluid from the jets, the stator having on each side of the ring member an annular passage communicating with the portions containing the blades, said latter passages being connected in the two members in the said lateral passages in the stator, the stator having an axial outlet passage in the 100 shaft on one side having passages connecting the latter passage with the said circular passages.

6. In a rotary motor, a rotor having a circular channel in one side face, and a series 105 of metallic blades substantially trough-shape with extensions at each end, the blades having the extremities only embedded in the 110

opposite walls of the channel, and inclined slightly to the radius of the member.

opposite walls of the channel, and a stator having jets on opposite sides arranged to direct the fluid to the said buckets.

7. In a rotary motor, a rotor having a circular channel in one side face, and a series of metallic blades substantially trough-shape with extensions at each end, the blades having the extremities only embedded in the
